UNITED STATES PATENT OFFICE.

HALBERT B. HALVORSEN, OF CHICAGO, ILLINOIS, ASSIGNOR TO SULLIVAN MACHINERY COMPANY, A CORPORATION OF MASSACHUSETTS.

FLUID-OPERATED PUMPING SYSTEM.

1,426,862.

Specification of Letters Patent. Patented Aug. 22, 1922.

Application filed May 20, 1919. Serial No. 298,466.

To all whom it may concern:

Be it known that I, HALBERT B. HALVORSEN, a citizen of the United States, residing at Chicago, in the county of Cook and State of Illinois, have invented certain new and useful Improvements in Fluid-Operated Pumping Systems, of which the following is a full, clear, and exact specification.

My invention relates to fluid operated pumping systems, and more especially to a pump or foot-piece for mixing an aerating fluid with a liquid to be pumped.

One object of the present invention is to provide an improved pump for an air lift system. Another object of the present invention is to provide an improved means for mixing an aerating fluid with a liquid to be pumped. Still another object of the present invention is to provide an improved form of foot-piece which is easily and cheaply made, and which may be easily assembled and attached to the cooperating fluid conductors of a pumping system. These and other objects and advantages of my improved construction will, however, hereinafter more fully appear.

In the accompanying drawings I have shown for purposes of illustration one embodiment which my invention may assume in practice.

In these drawings,—

Fig. 1 is a longitudinal sectional view of my improved foot-piece, taken on line 1—1 of Fig. 2.

Fig. 2 is a transverse sectional view thereof substantially on line 2—2 of Fig. 1.

Fig. 3 is a detail sectional view taken on line 3—3 of Fig. 1.

In this illustrative construction I have shown a foot-piece casing 1 having adjacent its upper end a venturi outlet 2 to a riser 3, to which the casing is attached as by a threaded connection therewith. The casing 1 also has a connection with a down pipe 4 or aerating fluid conductor 4, from which pressure fluid, as compressed air, is admitted to the interior of the casing through the passageway 5, herein shown as formed within the walls of the casing.

The compressed air in the foot-piece mixes with the water or other liquid to be pumped, which enters the foot-piece, preferably through the bottom thereof, as through a bell-mouth 6 formed on the lower end of a

pipe or shell 7, herein shown as substantially cylindrical and as being attached to the casing by a threaded connection, as shown at 8. The pump element 7 preferably has a fluid tight connection with the lower end of the connection, as by means of a packing 9, to prevent the air from leaking out of the foot-piece into the space between the casing and the wall of the hole during the operation of the pump. Threaded, preferably centrally, into the shell or pipe member 7, and preferably into a hub 10 formed centrally in the foot-piece and attached thereto as by hollow webs 11, is a central perforated pumping member 12, herein shown as conical with the smaller end thereof pointed toward the eduction pipe 3. As the water enters the bell-mouth 6, it is separated by a depending point 12', preferably carried by the pump element 12, into a cylindrical column, usually termed a sheet, the water passing upward past the hollow webs 11 into the space between the pump elements 7 and 12. In order that the webs 11 may impede the flow of the water as little as possible, the upper and lower edges thereof are preferably V-shaped, as shown at 11' in Fig. 3. The air which enters the foot-piece from the passageway 5 passes through the hollow web 11 to the central conical member 12 and is directed from the inner bore thereof through a plurality of small passages 13, which are preferably bell-mouthed at their outer ends, into the water, which it emulsifies, lightens, and lifts in a well known manner.

While different means may be used for directing a flow of pressure fluid from the passageway 5 to the pump element 12, I preferably provide a plurality of radial slots 14 which may be aligned with the hollow interiors of the webs 11 to receive a flow of fluid therefrom and direct it into the hollow interior of the element 12. Since the slots 14 may not always be aligned with the webs 11 I provide between the hub 10, connecting the webs 11, and the perforated pump member 12 carried thereby, an annular recess 15 which is always in communication with the slots 14 and the hollow webs 11.

The efficiency of a pumping system of this kind depends to a large extent upon the degree of emulsification of the water by the air in or just above the pump or foot-piece,

- and since, especially in the larger pumps used, the injection of air into a sheet of water or other liquid from one side thereof does not thoroughly emulsify or mix the air with the water, I preferably provide means for injecting the water into a sheet on both sides of the latter. For this purpose, I have provided between the pump element 7 and the casing 1, a space 16 which is always in communication with the inlet 5, the pump element 7 being also provided with a plurality of injecting passages 17, herein shown as similar to the injecting passages 18, for directing air from around the shell 7 into the outside of the sheet, which flows upward between the central member 12 and the shell 7 from the bell-mouth 6. Since the inner surface of the shell 7 is considerably larger than the outer surface of the conical member 12, I preferably space the injecting passages 17 further apart in the shell 7 and also preferably intersperse some of the passages 17 in the shell 7 between some of the passages 13 in the central piece 12, so that the water, as it passes up between the two pumping elements 7 and 12, is acted upon alternately on opposite sides by successive jets, with the result that the air is more thoroughly mixed with the water because of the churning motion given to the latter. The shell 7 is preferably made as a separate piece and detachably connected to the casing 1, and the inner pumping member 12 is preferably made separate from the shell 7 and detachably connected to the foot-piece, so that these parts may be made separately and thereby reduce the cost of manufacture and facilitate the replacement of broken parts and the inspection of the foot-piece.
- It is thus seen that I have provided a novel and improved means for injecting an aerating fluid into both sides of a sheet of liquid to be elevated, and that I have provided an improved injecting means for directing a flow of gas under pressure into a liquid in such a manner that the two are thoroughly mixed and that no pressure fluid is lost during the emulsifying of the liquid. It should also be noted that I have provided an improved foot-piece for air lift pumps which is easily constructed, easily assembled, and which may be attached to air lift systems now in use without any modification whatever in these systems.
- While I have in this application specifically described one embodiment which my invention may assume in practice, it is to be understood that this form is used for illustrative purposes only and that the invention may be modified and embodied in various other forms without departing from its spirit or the scope of the appended claims.
- What I claim as new and desire to secure by Letters Patent is:
1. In an air lift pump, a nozzle having provision for directing aerating fluid into intersecting jets whose axes lie in planes including the axis of the nozzle, the points of intersection lying in a surface of revolution.
2. In an air lift apparatus, a nozzle having means for discharging a part of an aerating fluid in a jet, and means for discharging another part of the aerating fluid in an intersecting jet, said jets and the apex of the angle made by their intersection lying in a plane passing through the axis of the nozzle, but said apex being spaced laterally from said axis.
3. In an air lift apparatus, a nozzle having a member for discharging a part of an aerating fluid in a jet, and a member for discharging another part of the aerating fluid in an upwardly directed intersecting jet at a point above said first named jet.
4. In an air lift pump, means comprising pointed deflecting means for forming a liquid entering the pump into a sheet, and means for discharging a compressed fluid into both sides of said sheet.
5. In an air lift pump, means comprising pointed deflecting means and a coaxially disposed casing for forming a liquid entering the pump into a sheet, and oppositely disposed means for discharging a compressed fluid into both sides of said sheet.
6. In a foot-piece for air lift apparatus, an air intake, a substantially cylindrical member having provision for separating a part of the air into a plurality of jets, and a conical member having provision for separating another part of the air into a plurality of jets, said members cooperating to form the liquid to be aerated into a sheet and to confine it in sheet form during aeration by said jets.
7. In a foot-piece for air lift apparatus, an air intake, a substantially cylindrical member having provision for separating a part of the air into a plurality of jets, and a conical member having provision for separating another part of the air into a plurality of jets, said last named jets intersecting said first named jets.
8. In a foot-piece for air lift apparatus, an air intake, a substantially cylindrical member having provision for separating a part of the air into a plurality of jets, and a conical member having provision for separating another part of the air into a plurality of jets, said conical member being disposed within said cylindrical member and said last named jets being directed in the opposite direction from said first named jets.
9. In a foot-piece for air lift apparatus, an air intake, a substantially cylindrical member having provision for separating a part of the air into a plurality of jets, and a conical member having provision for separating another part of the air into a plu-

rality of jets, said conical member being disposed within said cylindrical member and a part of the jets in said members being in staggered relation.

- 5 10. In a foot-piece for air lift apparatus, an air intake, a substantially cylindrical member having provision for separating a part of the air into a plurality of jets, and a detachable conical member having provision for separating another part of the air into a plurality of jets.

10 11. In an air lift pump, a foot piece comprising means for dividing the ascending column of liquid into an unbroken annulus, 15 and means for simultaneously aerating said annulus from both sides thereof.

15 12. In an air lift apparatus having an eduction pipe, a foot-piece adapted to be attached to the eduction pipe, a liquid inlet 20 carried by said foot-piece, and a plurality of oppositely disposed means between said inlet and the part of the foot-piece attachable to the eduction pipe for mixing an aerating fluid with the liquid to be pumped.

20 25. 13. In an air lift apparatus having an eduction pipe, a foot-piece adapted to be attached to the eduction pipe, a liquid inlet carried by said foot-piece, and a plurality of means between said inlet and the part of the 30 foot-piece attachable to the eduction pipe for mixing an aerating fluid with the liquid to be pumped, one of said means being detachably secured to the foot-piece.

30 35. 14. In an air lift apparatus, a pump comprising a casing, through which the liquid to be pumped is adapted to flow, a fluid flow directing means mounted in spaced relation thereto, and jet means opening through the wall of said casing for supplying an aerating fluid to the space between said casing and said fluid directing means.

40 45. 15. In an air lift apparatus, a pump comprising a casing through which the liquid to be pumped is adapted to flow, a detachable fluid flow directing means mounted thereon in spaced relation thereto, and jet means opening through the wall of said casing for supplying an aerating fluid to the space between said casing and said fluid directing means.

50 55. 16. In an air lift apparatus, a pump comprising a casing, a fluid aerating means mounted in spaced relation thereto, means for supplying an aerating fluid to the space between said casing and said fluid aerating means, and a second fluid aerating means detachably secured to said casing and com-

municating with the space between said casing and first named means.

17. In an air lift apparatus, members co-operating to form between them a passage annular in cross section for the flow of a liquid to be aerated, said passage communicating at its top with a riser pipe and progressively increasing in flow area from 60 a point adjacent its inception to its end adjacent said riser pipe, and means for discharging aerating fluid into a liquid in said passage, said means discharging into said passage through the outer periphery thereof. 65 70

18. In an air lift apparatus, members co-operating to form between them a passage annular in cross section for the flow of a liquid to be aerated, said passage communicating at its top with a riser pipe and 75 progressively increasing in flow area from a point adjacent its inception to its end adjacent said riser pipe, and means for discharging aerating fluid into a liquid in said passage, said means discharging into said 80 passage both through the inner and through the outer peripheries thereof.

19. In an air lift pump, a foot piece comprising an annular chamber having a connection with a source of pumping fluid and 85 having a central longitudinal bore through which the liquid to be pumped may pass and also having orifices in the inner wall of the chamber discharging into said bore, and a centrally disposed, hollow member supported within said bore and cooperating with the inner wall of said chamber to form the liquid into an elongated annular sheet, 90 said member also having orifices in its walls and a connection with a pumping fluid supply whereby pumping fluid may be discharged into the inner wall of the annular liquid sheet. 95

20. In an air lift pump, a foot piece comprising an annular member and a member 100 centrally disposed therein and supported by at least one arm projecting from said annular member, said annular and central members cooperating to form an elongated generally annular passage for liquid to be 105 pumped and having each within it a pumping fluid supply chamber and having orifices opening through the walls thereof into said annular passage, and means for supplying pumping fluid to both of said chambers including a passage through said arm. 110

In testimony whereof I affix my signature.

HALBERT B. HALVORSEN.
